METHOD OF AND MEANS FOR REDUCING
THE EFFECTS OF ELECTRICAL DISTURB-
ANCES

David G. McCaa, Lancaster, Pa.

Application August 6, 1929, Serial No. 383,932

24 Claims. (Cl. 250—20)

My invention relates to improvements in means for reducing and limiting interfering pulsations in electric circuits through which electrical energy is being transmitted in useful form; and especially to apparatus and methods adapted to diminish the influence of atmospheric or any other electrical disturbances in signal receiving devices, originating externally of the device; and is a continuation in part of the invention disclosed in my co-pending application, Serial No. 320,849 filed November 21st, 1928, which, in turn, is a division of my application, Serial No. 74,087, filed December 8th, 1925.

As is well known, when electrical disturbances are in evidence during radio reception, they take the form of audible "noises" which often completely submerge all other reproduced sounds. The origin of such disturbances cannot be readily controlled, nor their arrival at the antenna prevented; hence the place where their effects may be decreased is confined to the vicinity of the receiving set itself. To lessen or eliminate the oscillations by which such disturbances are produced requires of course that such oscillations be, so far as possible, nullified; and one useful method of proceeding for this purpose is to decrease the amplitude of said oscillations, as compared with the amplitude of signal oscillations.

It is therefore the object of this invention to provide a method and an apparatus so designed that the effects of electrical disturbances can be controlled and greatly reduced, and in fact largely neutralized, without in any way affecting the quality of reception of the desired signals; thus eliminating interference and permitting the reception of the signals with virtually as much strength and clearness as when no disturbances are present.

A further object of the invention is to provide a method and apparatus that will enable the electrical disturbances to be divided into equal components and to be substantially reduced, and so controlled that the divided components oppose each other, and are thereby in large measure obviated; this result being accomplished by means of circuits and appliances which permit the signals to pass freely while the substantial reduction of the disturbances is being accomplished.

Another object of the invention is to provide a method and apparatus by which the effect of electrical disturbances may be reduced to a point where it is no longer troublesome, and which can be operated in connection with an ordinary radio receiving set; the apparatus in this respect

including appliances which can be disposed either between the set and the antenna, or connected into the circuit of the set between the point where the antenna is connected and the sound reproducing device.

A still further object is to provide apparatus for thus reducing the influence of electrical disturbances that can be easily and inexpensively constructed, that is reliable in operation and that can either be incorporated into a receiving set, or made up as an accessory to be connected to a radio receiving set in such manner as to give the desired results.

Other objects and advantages of the invention will appear from the following description taken in connection with the drawings.

On the drawings, Fig. 1 is a view showing diagrammatically an arrangement of circuits with the necessary appliances therein for realizing the objects of my invention;

Figs. 2 to 7, inclusive, are similar arrangements giving modifications; and

Fig. 2a is a graphic representation of the function of coils 12 and 15 of Fig. 2.

Referring first to Fig. 1, I show a pair of primary coils 1 and 2 in series, the terminals of these coils 3 being arranged one for the connection with the antenna (not shown), and the other with the ground in the usual way, or both to any other source of signal waves. Both coils 4 are adapted to transfer energy to a secondary 5. Adjacent to the coil 1 is a secondary coil 4 and cooperating with the coil 2 is a secondary 5. Each of the secondaries 4 and 5 has its terminals connected to the anodes of two thermionic two element vacuum tubes 7 and 8, 7' and 8' respectively. The cathodes of each pair of tubes 7 and 8, and 7' and 8' are in the form of the usual heated filaments, and are connected together and arranged to be supplied with current from common sources 9 and 9' respectively. The current of each source 9 and 9' can be controlled by a suitable rheostat connected with each of the cathodes. At 10 is a uni-directional current source, the positive terminal of which is joined to the cathodes of tubes 7 and 8 for the coil 4, and the negative terminal of which is connected to the anodes or plates via the mid-point of the secondary 4. This secondary is thus in effect divided into two coils, the upper of which is operatively associated with the adjacent tube 7 and the lower with the adjacent tube 8. The circuit of the secondary 5 includes similar tubes 7' and 8' and a uni-directional current source 10', but this source is reversed with respect to the source 10.

105 110

10 and has its negative terminal connected to the filaments of the adjacent tubes 7' and 8' and its positive terminal connected through the midpoint of the secondary 5 to the anodes or plates. 7' and 8' connected to the lower coil 5. As soon as current flows in the circuits of the secondary 4, the flux generated by the coil 1 is intercepted and disturbed by the two halves of the secondary 4. Similarly, the disturbing oscillations and the signal oscillations passing through the coil 2 inductively influence the coil 5 and current will flow in the circuits of this coil as before alternately through the tubes 7' and 8' therein. The current in the circuits of the coil 4, however, will be proportional to the disturbing oscillations only; while the current in the circuit of coil 5 will be proportional to both the disturbing and the signal oscillations and will be larger to that extent. The flux of the coil 2 will thus be largely intercepted by the secondary 5, while the magnetic flux of the coil 1 is intercepted only to the extent that is produced by the disturbing oscillations in coil 4, and since the primary coils 1 and 2 are arranged in opposition, the effect of the disturbing oscillations will be substantially nullified and only the signal oscillations will be transmitted by the secondary 6 to the receiving set. 80

5 Obviously, a single uni-directional current source could be used in place of sources 10 and 10' or sources 9 and 9'. The positive and negative terminals of sources 10 and 10' may be connected to combine them as a common source. 10 Likewise, the positive and negative terminals of sources 9 and 9' may be connected to combine them as a single source. However, it is important to note that only one of these two connections may be made, since if both were made in the same 15 system, a short circuit would be placed across source 10 or source 10'. Since a showing of the sources as indicated might be confusing, they have been shown as independent sources, but the above-mentioned modification is an obvious 20 one. 85

The coils 1 and 2 are arranged in opposition; that is they are so wound or poled that the passage of current through them causes the magnetic flux of one coil to oppose that of the other. 25 Further the voltage of the source 10 is selected so as to be substantially equal to the peak voltage of the oscillations carrying the signals. 90

Suppose, for example, signal oscillations are coming in and pass through both coils 1 and 2. 30 As these coils are in opposition, they have no direct effect upon the secondary 6; and as the voltage of the oscillations is no greater than that of the source 10, the anodes or the plates of tubes 7 and 8 connected with the coil 4, which 35 are at a negative potential because they are connected with negative terminal of the source 10, remain negative. Hence there is no flow of space current between the anodes and the cathodes of the tubes 7 and 8 of the coil 4; and the circuit of 40 the coil 4 remains inoperative. On the other hand, the anodes of the tubes 7' and 8' connected to the coil 5 are always positive because they are connected to the positive terminal of the source 10'. Hence signal oscillations passing through 45 the coil 2 induce corresponding oscillations in the coil 5. When the upper end of the coil 5 is positive, the oscillations pass through the tube 7'; while the lower end of coil 5, which is connected to the anode of the tube 8', is at the same 50 time negative, no oscillations pass through the tube 8'. Similarly, when the lower end of the coil 5 becomes positive, the upper end becomes negative and oscillations pass through the tube 8' but none through the tube 7'. The tubes 7' and 55 8' thus act as resistors to both halves of the incoming signal wave and the magnetic flux from the coil 2 is disturbed and intercepted by the two 60 circuits of the coil 5, unbalancing the system and enabling the primary 1 to generate a substantially unopposed voltage in the secondary 6. Hence signals are transmitted to the circuits connected to the coil 6. 105

The upper coil 4 with its halves connected to valves 7 and 8, having a negative potential higher than the peak signal potential on the anodes due to connection with the negative terminal of the source 10, permits no signal current to flow into the tubes 7 and 8 at this time. 110

If now atmospheric or other electrical disturbances of high amplitude occur and flow into the coils 1 and 2 with the signal oscillations, the voltage induced in the coil 4 will be much higher than that of the source 10. In this case, the tubes 7 and 8 connected to the coil 4 will pass current 115 through their plate circuits and so will the tubes 75

of the coils 12 and 15, i. e., when signal voltages traverse the winding 1, there will be no effect on the coils 12 and 15 because the voltages are of insufficient value to affect the impedances of the 5 coils 12 and 15, but as soon as disturbing voltages, which are generally surges of high amplitude, traverse the winding 1, they induce correspondingly high voltages across the coil 4' thereby materially decreasing the impedance of coils 12 and 10 15 and permitting considerable current to flow in the circuit of 4'.

This function may be more clearly understood when explained by means of the graphical illustration shown in Fig. 2a. Curve *a* is the 15 current-impedance characteristic or saturation curve of the coil 12. It may be noted that the impedance remains constant until the saturating current I_{12} reaches the point *i* where it begins to take a sudden drop and continues to decrease 20 with an increase of current. It is this saturation point *i* that is made use of in the device of the invention. The direct current from the source 17 is set at such a value as *c* where a substantial increase in current beyond that point will 25 decrease the impedance of the coil 12. Now if signal currents, which are small as indicated by *d* in Fig. 2a, traverse the winding 12, they 30 will have very little or substantially no effect on the impedance of the coil as indicated by the curve in the region of the point *i* on the curve *a*. On the other hand when disturbing currents 35 traverse the winding 12 as indicated by *e* in the figure they reduce the impedance considerably as indicated by the point *g*, and consequently the impedance of the circuit 4 is reduced and 40 considerable current will flow thereby disturbing the flux of coil 1 and effectually absorbing substantially all of the voltages or surges from coil 1 while permitting the signal voltages to remain in the circuit of coil 1.

It will be noted from Fig. 2a however that the coil 12 takes care of only one-half of each cycle, that is the portion to the right of the point *i* in decreasing the impedance of the coil. Therefore 45 the coil 15 is provided in parallel with coil 12 and arranged in such a way as to take care of the opposite half of the cycle, i. e., when the top of coil 12 is positive the top of coil 15 will be negative and in this way both halves of the alternating current wave in coil 4' are taken care of. The curve *b* in the Fig. 2a is the curve of coil 15.

The operation of the coils 12 and 15 together with primaries 1 and 2 and secondaries 4', 5' and 55 6 is as follows:—The coils 1 and 2 are wound or poled so that the magnetic flux produced in them is equal and opposite and when signal oscillations alone come in at the terminals 3, the coils 1 and 2 being balanced produce no effect in the secondary 6. Coil 5' being closed through the resistance 18, the signal oscillations create a magnetic flux in primary 2 which is largely 60 intercepted or absorbed by the coil 5' thereby unbalancing the system and the same oscillations in coil 1 induce a current in the coil 6 permitting the signal to go to the receiving apparatus. At 65 this time, the circuit of coil 4' is substantially open circuited because the signal voltages are not sufficient to increase the saturation of the cores 11 and 14.

70 When disturbing oscillations or undesired electrical surges arrive together with the signal oscillations, the amplitude is of course much greater and considerable current flows in the circuit of coil 5' disturbing and intercepting the magnetic flux of coil 2 as before, so that it has only

a slight effect on coil 6; this slight effect being balanced out by the equal and opposite effect in coil 1. Now coil 4' also draws current because of the effect of the disturbing voltages on the saturated cores 11 and 14 through coils 12 and 15 but only to the extent that the current induced by the disturbing oscillations is substantially absorbed or intercepted from the coil 1 and the signal oscillations are permitted to remain which are in turn induced by the primary 1 into secondary 6 and are transmitted to the receiving apparatus.

It is readily seen that the function of coils 4' and 5' of Fig. 2 is the same as in Fig. 1, that is, coil 5' absorbs substantially the total flux produced by both disturbing and signal oscillations in coil 2 while coil 4' absorbs from coil 1 substantially only that portion of the flux which is produced by the distributing oscillations. The system is thereby unbalanced and primary 1 induces the signal current into secondary 6 which transmits it to the receiving device. The purpose of choke C in circuit 5' is to cause the phase angles of the two circuits 5' and 4' to be substantially equal when disturbing oscillations flow in circuits 4' and 5'.

In the modification shown in Fig. 3, the coils 1 and 2 are in the same relation as before, and the coil 5' has its terminals connected to the coil 19. Between coil 1 and one terminal 3 is 105 a transformer having a primary coil 20 and a secondary coil 21. Another transformer is connected with its primary 25 in series with the secondary 21. This transformer is used solely for producing proper phase relation between the 110 voltages across the coil 19' and coil 4' and is not in inductive relation with either coils 20 and 21 or 1 and 4'. One terminal of the secondary 26 is connected to the grid of an amplifier vacuum tube 22, and the other is joined to the filament of 115 this tube. The anode of the tube 22 is connected to the positive terminal of the battery 24 and a primary coil 23, also joined to the filament of the tube 22; and this coil 23 is in inductive relation with a secondary coil 19' in the circuit of the 120 secondary 4'.

With this arrangement, disturbances and signals together are absorbed by the action of the lower secondary coil 5', and disturbances only by the upper coil 4'. The method of keeping the upper secondary 4' to all intents and purposes open, so far as signal in primary 1 is concerned, is to subject it to the influence of an equal and opposite potential which must not exceed the peak potential of the signal. When signal oscillations arrive, the primary coil 2 causes current to flow in the coil 5' and its flux is intercepted so that it substantially does not act upon the secondary 6. The signal oscillations also act through the primary 20 and so influence the amplifier tube 22 that the plate current thereof varies between maximum and zero. Hence in the coil 19' there is generated a voltage that is equal and opposite to the voltage produced in the secondary 4' by the coil 1, as indicated by signs and arrows. The coil 4' thus remains practically open and the flux of the coil 1 links with the coil 6 to transmit the signal to the receiving apparatus.

When signal and disturbing oscillations arrive together, the circuit of the lower coil 5' becomes active as before and intercepts almost all the flux from the coil 2. At the same time, the primary 20 transfers the combined oscillations which are of much higher amplitude through circuit 21, 25 to the coil 26; but in the circuit of this coil 26, 150

the oscillations now cannot be amplified because the vacuum tube 22 becomes saturated or goes to zero before each oscillation or surge reaches its maximum value. The transfer of energy from 5 coil 23 to the coil 19' is therefore proportional only to the signal strength, and reduces the voltage in the coil 4' accordingly. Therefore, the effective voltage of the coil 4' will be in proportion to the intensity of the disturbing oscillations only, 10 and the flux of the primary 1 will not be wholly intercepted by the coil 4'. The portion of the magnetic flux of the coil 1 due to signal oscillations can inductively affect the coil 6 and the signal will be passed through again with the disturbances substantially reduced.

Another form of this modification may be made using two tubes A and B in parallel relation, as 20 shown in Fig. 3a with the grid of one tube biased positively and the grid of the other tube biased negatively, in place of the single tube 22 shown 25 in Fig. 3. This arrangement overcomes the difficulty which might arise from the variation of the saturation point of vacuum tubes now in commercial use and which might not be taken care of in the circuit of Fig. 3. In Fig. 3a, the positively biased tube A passes both the disturbing oscillations and the signal oscillations while the negatively biased tube B passes only the disturbing oscillations because the value of the 30 biasing voltages is equal to or greater than the peak signal voltage. Consequently, when the positive peak of the signal voltage acts on tube A plate current flows but when the negative peak of the signal acts on tube A the plate current falls 35 to zero. The negatively biased tube B, however, remains inactive to both peaks of signal voltage. When the positive peak of the disturbing voltage acts on the tube A, plate current will flow as in the first case but when the negative peak 40 acts on tube A, the plate current falls to zero and beyond. When the positive peak of the disturbing voltage acts on tube B, plate current will also flow but will oppose the plate current of tube A in coil 23 so that there is no output due to 45 disturbing voltages and only the plate current of tube A due to signal voltages will be translated from coil 23 to coil 19'. This may be more easily understood from the following table, in 50 which it is apparent that signal is transferred without opposition, and disturbances generate substantially equal currents in both tubes.

Grid voltage	Plate current of tube A in coil 23	Plate current of tube B in coil 23
55 Signal+wave.....	Increases.....	Zero.
Signal-wave.....	Decreases to zero.....	Zero.
Disturbance+wave.....	Increases largely.....	Increases largely.
Disturbance-wave.....	Decreases to zero.....	Zero.

60 In Fig. 4, the circuits comprise primaries 1 and 2 wound so that their magnetic fluxes are in opposition and connected to terminals 3 as before, with the secondaries 4' and 5', associated with coils 1 and 2, respectively, and the secondary 6 65 between the primaries 1 and 2 and associated with both. The lower secondary 5' has the coil 19 in its circuit and the upper secondary 4' has the coil 19'. At 43 is a local source of alternating current connected in circuit with two coils 70 44 and 44' which are in inductive relation to the coils 19 and 19', respectively. This source 43 generates a synchronous alternating current, being a current of the same frequency and substantially the same amplitude as the signal current to hold the secondaries 4' and 5' open. The

coil 19 is adjacent coil 44 and the direction of the current from the source 43 is such that the signal voltage across the upper secondary 4' is opposed in amplitude and phase by the voltage induced in coil 19' from the source 43 while the signal voltage across the lower secondary 5' is in phase with the voltage induced in coil 19 from source 43, as the arrows and signs indicate. For signals alone the circuit of the lower coil 5' only will be energized to intercept the flux of primary 2, so that the coil 6 is affected by the magnetic flux of the coil 1, substantially no current flowing in the coil 4', because the signal current is opposed by the current from source 43. When signals and disturbances come in together, the same result occurs with regard to the coil 5', but the oscillations of larger amplitude will now take effect in the coil 4' to overcome the voltage due to the local source 43. The current in the coil 4' will again not be as great as current 90 in the coil 5', leaving the primary 1 unbalanced to an extent proportional to the amplitude of the signal oscillations to take effect on the coil 6 and to transmit the signals. The arrangement of Fig. 4 does not transfer local oscillations 100 into the circuit of terminals 3-3 because coils 19 and 19' are arranged in opposed relation with respect to the input. If desirable a non-synchronous frequency may be used, in which case coils 4' and 5' alternatively function to absorb 105 the opposing signal flux.

In Fig. 5, coils 1 and 2 are in opposition as before and are connected to the antenna 25 and to the ground, with an adjustable condenser 26 in the antenna circuit. The coil 6 in the same 110 position as before is bridged by an adjustable condenser 42. The secondary 5' cooperating with the primary 2 is in circuit with an adjustable resistance 18. The coil 1 cooperates with a secondary in two sections, consisting of coils 27 115 and 28. These coils are connected through coil 29 in series; and the mid-point of the coil 29 is united by the connector 32 with the connection joining the two cathodes of a pair of three-element vacuum tubes 31, 31. The other terminals 120 of the coils 27 and 28 are connected with the anodes of the tubes 31 and the cathodes are supplied with current from source 9. A coil 33 is in inductive relation to coil 29 and the opposite terminals of this coil 33 are joined to the 125 grid and filament of another three-element amplifying vacuum tube 35. The grids of the tubes 31 are joined to the opposite ends of the two coils 38 and 39, in series; making a single coil in inductive relation to coil 37 which is in circuit with the uni-directional source 36 across the anode and filament of the amplifier tube 35. A direct current source 10 united to the common terminal of the coils 38 and 39, and to the cathodes of tubes 31 biases negatively 130 the grids of tubes 31.

In this arrangement, the primary input and the secondary output circuits are tuned. A voltage will be generated across the windings 27 and 28 by both the disturbing oscillations but 140 the signal voltages will not cause current to flow in the anode circuits of tubes 31 because they are not enough to overcome the negative bias on the grids produced by source 10. The disturbing voltages being of much greater amplitude oppose the effective negative bias on the plates and cause a current to flow in the anode circuits of the tubes 31. This anode current flowing through coil 29 induces a voltage across coil 33 which acts on the amplifier tube 35. Here 145 150

- the voltage is amplified and transferred by the windings 37, 38 and 39 to the grid-filament circuits of the two valves 31, 31. The amplified voltage may be higher than the voltage of source 5 10 and consequently may overcome the grid biasing potential and a substantially increased current flows in the anode circuits of tubes 31 thereby enhancing the action of coils 27 and 28 in substantially the flux from primary coil 1 produced by the disturbing oscillations. 10
- The purpose of this circuit is to cause the valves 31 to operate with increased effect by reason of lower impedance as compared to the valves in Fig. 1 which are not connected to an 15 amplifier. When this system is considered as a trigger-actuated system the effect becomes more apparent. Detuning also takes place in the primary and secondary tuned circuits. 15
- Hence when signals come in, the lower secondary 20 5' as before prevents the coil 2 from energizing coil 6; unbalancing the system and allowing coil 1 to transmit the signals through its inductive effect on coil 6. Inasmuch as the grids of the tubes 31 are biased, the signal voltage will be insufficient to cause a flow of current in the 25 valves 31 and the secondary circuit of the coils 28 and 29 remains open. 25
- When signals and disturbances come in together, current corresponding to both flows in the coil 5', drawing substantially all the magnetic flux of the coil 2 away from the coil 6; but in the secondary circuit of the primary 1, a somewhat smaller current will flow in the circuit of coils 27 and 28 and between the plates and filaments of tubes 31, due to the biasing effect of battery 10, and the current thereby induced in the winding 33 is amplified by the tube 35 as above set forth. The current acts through the transformer coils 37, 38 and 39 and so affects the 30 grids of the valves 31 that current through the plate circuits of the valves 31 is increased. This current enables coils 27 and 28 to intercept the major part of the flux of the primary 1, due to disturbing surges, and the coil 1 thus affects coil 35 6 only enough to induce oscillations therein corresponding to the strength of the signals. Thus 40 the effect of electrical disturbances or undesired oscillations of high amplitude is reduced to a minimum. Fig. 6 again corresponds to Fig. 1, 45 except that no secondaries are used and crystals or heater tubes or other asymmetric conductors are substituted for the tubes shown at 7 and 8 in Fig. 1. The coils 1 and 2 are wound in opposition upon the opposite ends of an iron core 46 which may have a central leg 46. This iron core 50 is used to make the system more effective at 55 audio frequencies. Cooperating with the coil 1 is a coil 47 and cooperating with coil 2 is a coil 48, these two coils 47 and 48 are connected in 60 series and lead to the receiving set. Across primary coil 1 are connected two pairs of crystals or other asymmetric conductors 50a with a D. C. source 51 in such a manner that one pair of crystals will permit one half of an alternating 65 current to pass through while the other will permit the other half to go through as in a full wave rectifier. The voltage of source 51 is set at a value equal to or greater than the peak voltage of the signals so that no signal oscillations 70 can traverse the valve circuit 50. In parallel with primary 2 is an adjustable resistor 49. 75
- The coils 1 and 2 would generate equal and opposite voltages in secondary coils 47 and 48 if it were not for the presence of the resistance 49 and the valve circuit 50 containing crystals
- 50a and the D. C. source 51 connected as shown. When signal oscillations arrive at the terminals 3 they are partially shunted and dissipated by resistance 49 thereby causing primary coil 2 to generate less voltage in secondary 48 than the primary 1 generates in secondary 47 because the valve circuit cannot by-pass the signal voltages due to the potential of source 51. In this way the coils 47 and 48 are unbalanced and signals are transmitted to the receiving apparatus. 80
- However when disturbing oscillations arrive at terminals 3 together with signal oscillations the resistor circuit 49 absorbs both while the valve circuit absorbs only to the extent to which disturbing oscillations are present, the desired oscillations thereby generating the signal voltages in secondary 47 which are transmitted to the receiving circuit. 85
- Fig. 6a shows a modification of a valve circuit which can be used in place of the valve circuit 50 in Fig. 6 or in place of tubes 7 and 8 in Figs. 1 and 7. Two tubes 50b are substituted for the crystals 50a in Fig. 6 and are reversely arranged, the anode of one and the cathode of the other are bridged by a direct current source 51 and 100 the resistance R in parallel with the source while the opposite electrodes are directly connected. 95
- In Fig. 7, the antenna 25 is connected through an adjustable condenser 26 and two sets of coils 1, 52 and 2, 53 in parallel to ground. The coils 105 1 and 2 are arranged in opposed relation to each other as in Fig. 1. The coil 52 at the left is inductively related to a secondary made up of two windings 54 and 55 in series. These windings are connected to the anodes of two two-electrode 110 thermionic vacuum tubes 7 and 8, and their common terminal is connected to the filaments of these tubes through a source 10 with an adjustable voltage divider across its terminals, the arrangement being similar to that shown in Fig. 1 115 for coil 4. At the right, the coil 53 is in inductive relation with secondary 5', which is shunted by a variable resistance 18. In inductive relation with the primary coils 1 and 2 is the output coil 6 which is shunted by the variable condenser 42. 120 The terminals of the coil 6 and condenser 42 are connected to the grid and filament of a detector tube 35'. In circuit with the grid are the usual leak resistance 57, and grid condenser 58; and the plate of tube 35' is connected through a unidirectional source of voltage 59 and telephones or loud speaker 60 to the filament of the tube. In the circuit leading to the grid is a primary 19' which has a secondary 44' supplied with alternating current from the local source 43' controlled by a switch 56, if it be desired to use 125 heterodyne reception. 130
- In this circuit when signal oscillations alone arrive at the antenna they are divided so that a portion goes through coils 1 and 52 to ground while another portion goes through coils 2 and 53 to ground. The coil 53 being in inductive relation with the load circuit 5'-18 is effectively short circuited and its impedance decreased so that considerably more current flows through coil 140 2 than coil 1 because the impedance of coil 52 remains unchanged since the plate circuits of tubes 7 and 8 are effectively open circuited to signal oscillations by the biasing source 10. In this way coil 2 has a greater inducing effect than coil 145 1 on output coil 6 and signals are translated into the output circuit. 150
- When disturbing oscillations arrive alone the impedance of coils 52 and 53 is decreased equally because the tubes 7 and 8 draw current as well

- as the circuit 5'-18 and therefore equal currents flow in coils 1 and 2; but the coils are in opposition and the fluxes balance each other out so that no disturbances are transferred to output coil 6.
5. When disturbing oscillations arrive together with signal oscillations coil 53 draws more current than coil 52 because the impedance of coil 53 is decreased more than that of coil 52 to the extent that circuit 5'-18 is affected by the disturbing oscillations as well as signal oscillations while tubes 7 and 8 are affected only in proportion to disturbing oscillations. Therefore the coil 2 carries more current than coil 1, the difference being the amount of signal current. The disturbing components in coils 1 and 2 are equal and opposite and balance out while coil 2 translates the signal component to coil 6.
- The disturbing oscillations take the frequency to which the circuit is tuned by shock excitation while the signal oscillations retain their normal frequency and are slightly attenuated by the detuned circuit. Consequently the primary and secondary circuits are detuned from each other when disturbing oscillations are present and therefore only a low transfer of energy takes place.
- All of the modifications described are adapted to be used reversely, that is, the output may be used as the input and vice versa, and the circuits will function equally well. The device may be placed in circuit anywhere between the antenna and the reproducer.
- Although for purposes of illustration, description and explanation, I have shown the coils 1 and 2 as the input and the coil 6 as the output they may be interchanged and I desire to be limited only by the scope of the appended claims.
- I claim:
1. The method of reducing the effects of electrical disturbances on signal oscillations which comprises dividing said disturbances into components, substantially reducing said components and causing said components to oppose each other so that their effects on the signal oscillations are substantially eliminated.
  2. The method of reducing the effects of electrical disturbances on signal oscillations which comprises dividing said disturbances into components without frequency discrimination, substantially reducing said components and causing said components to oppose each other so that their effects on the signal oscillations are substantially eliminated.
  3. The method of reducing the effects of electrical disturbances on signal oscillations which comprises separating the disturbances from the signal oscillations in accordance with their amplitudes, dividing said disturbances into components, intercepting the major portion of said components and causing the remaining reduced components to oppose each other so that their effects on the signal oscillations are substantially eliminated.
  4. The method of reducing the intensity of electrical disturbances in radio reception which consists of producing magnetic fluxes in two coils which oppose in their effects on a third coil, reducing the value of flux from one coil when the amplitude of the current therein is low, and reducing the value of flux from the other coil when the amplitude of the current therein is high.
  5. The method of reducing the intensity of electrical disturbances in radio reception which consists in operating a pair of coils so that the magnetic flux of one coil opposes that of the other, intercepting the flux of one coil when the amplitude of the current therein is low, and intercepting the flux of the other coil only when the amplitude of current therein is high.
  6. The method of reducing the effects of undesired oscillations on desired oscillations which consists in producing a magnetic flux in a pair of coils having a common flux path by passing both the undesired and the desired oscillations through said coils and dissipating the flux of both of said coils to such an extent as to prevent the undesired oscillations from being translated into an output circuit while the desired oscillations are translated to said output circuit unopposed. 80
  7. The method of reducing the effects of undesired oscillations on desired oscillations which consists in operating a pair of coils so that the magnetic flux produced by both of said oscillations in each of said coils is equal and opposite and intercepting the major portion of the magnetic flux of one of said coils while intercepting only that portion of the magnetic flux which is produced by the undesired oscillations in the other of said coils and utilizing the remaining flux in said last mentioned coil to transfer a desired current into a secondary circuit. 85
  8. The method of separating desired oscillations from undesired oscillations which comprises operating a pair of coils having a common flux path in opposed relation to each other so that only one of said coils transfers said desired oscillations into an output circuit while the other of said coils transfers the undesired oscillations into a circuit in which they are dissipated. 90
  9. The method of separating desired oscillations from undesired oscillations which comprises operating a pair of coils in opposed relation to each other so that the undesired oscillations are dissipated from one of said coils and both the desired and undesired oscillations are dissipated from the other of said coils and translating the desired oscillations from the first mentioned coil into an output circuit and utilizing said desired oscillations to operate a receiving device. 100
  10. A device for separating desired oscillations from undesired oscillations comprising a plurality of coils substantially equally supplied with signal energy and in opposed relation, said coils having a common flux path, an output circuit, and means for controlling said coils so that only one of them translates the desired oscillations into said output circuit. 110
  11. A device for separating desired oscillations from undesired oscillations comprising a plurality of primary coils in series opposed relation, a plurality of secondary coils in inductive relation with said primary coils, one of said secondary coils being in the output circuit of said device, means associated with another of said secondary coils for rejecting the desired oscillations from said last mentioned secondary and causing them to be translated into said output circuit, and means associated with still another of said secondary coils for intercepting the undesired oscillations and causing them to be ineffective on said output circuit. 120
  12. Apparatus for separating desired oscillations from undesired oscillations comprising a plurality of primary coils in series opposed relation, a secondary coil in inductive relation with one of said primary coils, means associated with said secondary coil for rejecting the desired oscillations from said secondary, an additional secondary coil in inductive relation with another 130

- of said primary coils, means associated with said additional secondary coil for intercepting both the desired and undesired oscillations, and a third secondary coil in inductive relation with at least one of said primary coils for translating said rejected desired oscillations to a receiving circuit. 13. Apparatus for separating desired oscillations from undesired oscillations comprising a pair of coils connected in series and wound so that the magnetic fluxes of said coils are equal and opposite, a coil inductively related to said coils and a secondary circuit associated with each of said first mentioned coils and containing devices for causing the magnetic fluxes of said coils to be dissipated so as to suppress the undesired oscillations and allow only the desired oscillations to be translated into an output circuit. 14. Apparatus for reducing the effects of electrical disturbances on signal currents comprising a pair of primary coils connected in series and wound so that the magnetic fluxes of said coils are equal and opposite, a secondary output coil in inductive relation with said primary coils, a secondary circuit in inductive relation with each of said primary coils, one of said secondary circuits containing devices for causing the magnetic flux produced by the desired oscillations in one of said primary coils to induce a current in said output coil, and the other of said secondary circuits containing devices for causing the flux produced by both the desired oscillations and the undesired oscillations in the other of said primary coils to have substantially no effect on said output coil. 15. Apparatus of the kind described comprising a pair of primary coils in series opposed relation, a secondary output coil in inductive relation with said primary coils, a secondary circuit in inductive relation with each primary coil, a thermionic vacuum tube and a source of unidirectional current in each of said secondary circuits, the source in one of said secondary circuits having its positive terminal connected to the anode of its associated tube and the source in the other of said secondary circuits having its negative terminal connected to the anode of its associated tube, another terminal of each secondary circuit being connected to the cathode of its associated tube. 16. In combination with a pair of primary coils connected in series opposed relation, a secondary output coil in inductive relation with said primary coils, a pair of additional secondary coils in inductive relation one with each of said primary coils, a pair of thermionic vacuum tubes having their plates connected to the terminals of one of said secondary coils with a potential negative with respect to the cathodes applied to said plates through the mid-point of said secondary coil, and a second pair of thermionic vacuum tubes having their plates connected to the terminals of the other secondary coil with a potential positive with respect to the cathodes applied to said plates through the mid-point of said other secondary coil. 17. In combination with a pair of primary input coils substantially equally supplied with signal energy and in series opposed relation, an output secondary coil in inductive relation with said primary coils, a pair of auxiliary secondary coils in inductive relation with said primary coils, and means energized from the circuit of said primary coils for producing a voltage opposing the voltage of one of said auxiliary secondary coils. 18. In combination with a primary input coil, a pair of secondary output coils in series opposed relation and in inductive relation with said primary coil, a pair of auxiliary primary coils in inductive relation with said secondary coils, and means energized from the circuit of said secondary coils for producing a voltage opposing the voltage of one of said auxiliary primary coils. 19. An apparatus of the kind described comprising a pair of primary coils in series opposed relation, a secondary output coil, a secondary circuit coupled to each primary coil, a local source of voltage, and means for enabling said source to oppose the voltage in one secondary circuit and assist the voltage in the other. 20. Apparatus of the kind described comprising a pair of primary coils in opposed relation, a secondary output coil in inductive relation with said primary coils, a secondary circuit associated with each primary coil, one of said secondary circuits being closed through an adjustable resistance, a pair of secondary coils in series with a third coil in the other secondary circuit, a pair of vacuum tubes, each having a grid, plate and filament, the plates of said vacuum tubes being connected to said secondary coils and their filaments connected to the mid-point of said third coil, an amplifier tube having a grid, plate and filament, the grid of said amplifier tube being inductively coupled to said third coil and the plate of said amplifier tube being inductively coupled to the grids of said first mentioned vacuum tubes, and means for applying a negative bias to at least one of said grids. 21. Apparatus of the kind described comprising a pair of primary coils connected to each other, a common iron core on which said coils are wound, a pair of secondary coils in series, one associated with each primary coil, said secondary coils being connected in opposition, an adjustable resistance shunting one primary coil, and a circuit including an asymmetric valve shunting the other. 22. A device for separating desired oscillations from undesired oscillations comprising a pair of coils in series opposed relation, a coil in inductive relation with said coils, and an electrical circuit which is effectively open circuited to the desired oscillations and closed to the undesired oscillations in inductive relation to one of said first mentioned coils. 23. A system for reducing the effects of electrical disturbances on signal currents comprising an input circuit and an output circuit, an auxiliary circuit inductively coupled to one of said circuits and containing means for keeping said auxiliary circuit effectively open to signal currents and closed to the disturbing currents thereby causing said signal currents to be transferred to said output circuit. 24. The method of operating upon a complex wave of signal and static oscillations to improve the signal-static ratio which comprises dividing the complex wave into two opposing components, weakening one component and transferring it to an output circuit, and weakening the other component only for high amplitudes before transferring it to said circuit.

DAVID G. McCANNA.
